UNITED STATES PATENT OFFICE.

YORKE BURGESS, OF WASHINGTON, DISTRICT OF COLUMBIA, ASSIGNOR, BY MESNE ASSIGNMENTS, TO AMERICAN SIGNAL COMPANY, OF KANSAS CITY, MISSOURI.

ELECTRIC RAILWAY SIGNALING SYSTEM.

No. 892,359.

Specification of Letters Patent.

Patented June 30, 1908.

Application filed September 24, 1907. Serial No. 394,388.

To all whom it may concern:

Be it known that I, YORKE BURGESS, a citizen of the United States, residing at Washington, District of Columbia, have invented 5 a new and useful Electric Railway Signaling System, of which the following is a specification.

This invention relates to electrical railway signaling systems of that general class in which each train is provided with a dynamo or other source of electrical energy, and in which continuous bare conductors are employed along the whole length of the line for the purpose of continuously connecting the 10 trains, the conductors offering gradually decreased resistance as two trains thus serially connected approach each other until the current is sufficient to overcome the resistance and thus energize the signals on the 15 trains. In this general class of devices, it is necessary to employ pole changers when the trains are reversed, that is to say, the pole changing switch of all trains running east or north will be located in one position, and 20 when the train is reversed to run west or south the position of the switch is correspondingly changed, or in case of backing it becomes necessary for the engineer to change the switch. This places the system at a 25 disadvantage inasmuch as the engineer may forget to change the switch and thus render the signaling system useless, and the danger is materially increased where from habit the engineer relies on the warning signals to advise him of danger.

The principal object of the present invention is to provide a system in which pole changing switches are rendered unnecessary, the system being operable for trains running 40 in any direction, either forward or backward.

A further object of the invention is to provide a system of this class in which a pair of current conductors are arranged overhead in the form of trolley wires or on the roadbed in 45 the form of a third rail, and are engaged by two separate traveling contacts carried by each train, these current conductors zigzagging or crossing each other at intervals, so that each of the traveling contacts will be in 50 engagement with one of the conductors for a limited period, and then in engagement with the other conductor for a corresponding period, these contacts alternating and the shifts occurring with sufficient frequency in 55 the length of the latter to prevent the approach of trains within a dangerous distance without giving warning.

With these and other objects in view, as will more fully hereinafter appear, the invention consists in certain novel features of construction and arrangement of parts, hereinafter fully described, illustrated in the accompanying drawings, and particularly pointed out in the appended claims, it being understood that various changes may be made in the form, proportions, size and minor details of the structure without departing from the spirit or sacrificing any of the advantages of the invention.

In the accompanying drawings:—Figure 1 is a perspective view of an electric railway signaling system constructed and arranged in accordance with the invention. Fig. 2 is a diagram illustrating a modification of the invention.

Similar numerals of reference are employed to indicate corresponding parts throughout the several figures of the drawings.

In the present case each of the trains A and B is shown as provided with a known system of wiring and signaling devices. These include a dynamo 10 from one side of which leads a current conducting wire 11. From the opposite side of the dynamo leads 85 a wire 12, that is connected to a rheostat 13, designed to adjust the distance within which the system becomes effective for signaling purposes. From the rheostat leads a wire 14 to a group of incandescent lights 15, and 90 from these leads a wire 16. The two wires 11 and 16 are connected to traveling contacts 18 and 19. Also connected in this circuit is a shunt 20 including a high resistance 21, preferably in the form of a lamp, and in 95 the shunt is also connected a relay magnet 22 which, when the shunt is energized, attracts an armature 23, that closes a local circuit 24 with a storage battery 25, this battery 25 energizing a solenoid 26 that operates some 100 train controlling device, such, for instance, as the engineer's brake valve, or the steam cut off. This wiring system is so arranged that when trains approach each other within a sufficient distance to allow the dynamos to 105 overcome the resistance of the main line conductors, the lamps 15 will glow faintly at first, and then with gradually increasing brilliancy as the trains near each other, and the resistance of the line decreases. If the 110

engineer fails to heed the warning and the trains approach within such distance that collision is imminent, the high resistance 21 of the shunt will be overcome and the relay 5 magnet 22 will be energized, thereby closing the local circuit through the storage battery 25 and applying the train controlling device.

The invention in the present instance resides in the arrangement of the continuous 10 conductors 30 and 31, and it will be observed that these conductors cross each other at intervals, so that the contact 18 will be in engagement with conductor 30 for a limited period, and then with conductor 31 and 15 again with conductor 30, while the contact 19 will engage the conductors 31, 30, 31, in alternation.

The stretch of the conductors between intervals of crossing is so short that it will be 20 practically impossible for two trains to approach so near each other as to collide without getting a warning signal, and it will be observed that no pole changers or similar manually operable devices are employed, so 25 that neglect of the engineer or other person cannot render the system inoperative.

In the arrangement shown in Fig. 2 the trolley wires are formed in sections, and these sections are arranged in zigzag order. 30 Each section of trolley wire 30', 31' occupies a position first to the right and then to the left and the full length of each section is such that two trains may be in contact therewith at the same time without danger of collision, although under no circumstances can they approach within a distance of less than one half the length of a section without the signals being displayed on both trains and the length of this half section is ample to 35 give sufficient warning of the danger of collision. In wiring, the positive side of each dynamo is connected to the traveling contact 18' and the negative side is connected by a wire 40 and traveling contact 41 to the 40 wire 31' on the opposite side. From the wire 40 extends a wire 12' leading to the rheostat and through the other portions of the local apparatus in the same manner as previously described. In this case the wire 16' 45 which leads from the signals 15 and the relay magnet 22 is connected to a traveling contact 19' that is in engagement with one of the traffic rails x , the latter in this instance constituting the return conductor.

50 It will be seen that a current from the dy-

name of train A will pass to the traveling contact 18', thence through wire 30' to the contact 41, train B and from thence through wire 40 and wire 12' to the local wiring circuit of train B, thence down through conductor 16', the traveling contact 19', through the traffic rail x traveling contact 19' of train A, wiring system of train A, wire 12' and wire 40 back to the dynamo 10. In this case the dynamo of one train will energize the 60 signals of both trains, and two trains can not approach within a dangerous distance without receiving warning. At the same time it is possible for the engineer to determine whether the signal is from a train approaching in one direction, or a train approaching in the other direction. To accomplish this, switches 50 are introduced in the wires leading from the trolley wheels, and when the signal is received in the cab, the engineer can 65 open one or other of the switches to determine whether a signal is being sent by his own engine to a train ahead, or is being received from a train behind.

I claim:—

1. In electric railway signaling systems, a 70 source of electrical energy, a signaling means on each train, a pair of conductors crossing each other at intervals to present portions of their lengths alternately on opposite sides, 75 and a pair of traveling contacts arranged on each train and engaging said conductors, each contact engaging the conductors in alternation.

2. In electric railway signaling systems, a 80 source of energy, and a signaling means on each train, a pair of traveling contacts on each train, and a pair of continuous conductors, said conductors crossing each other at intervals throughout the length of the 85 system, so that each contact will engage said conductors in alternating order.

3. In electric railway signaling systems, a 90 source of electrical energy, a signal means on each train, a pair of traveling contacts on 100 each train, and a plurality of conductors each arranged to be alternately in the path of both contacts.

In testimony that I claim the foregoing as my own, I have hereto affixed my signature 105 in the presence of two witnesses.

YORKE BURGESS.
